FASTENING DEVICE FOR BELTS

William J. Dillenz, Philadelphia, Pa.

Application June 21, 1949, Serial No. 100,470

6 Claims. (Cl. 24—194)

1

This invention relates to fastening devices and more particularly to an improved belt buckle.

The primary object of the present invention is to provide a fastener which is simple in operation, cheap to construct, and which is adapted for fabrication from a wide variety of material, and for use with a wide variety of products.

A further object of the invention is to provide a fastener for bands, straps and the like which is positively locked by means of a transversely actuated wedge.

A still further object of the invention is to construct a locking device having a crimping action with respect to a belt passing between the edges of the apertured sleeve and a wedge slidably mounted therein.

A further object of the invention is to provide a novel belt buckle in which the fastening construction lends itself to the enhancement of the article.

Further objects will be apparent from the specification and drawings in which:

Figure 1 is a perspective showing my improved fastener as applied to a belt;

Figure 2 is an enlarged perspective detail of the locking wedge;

Figure 3 is a top view of the structure of Figure 1;

Figure 4 is a perspective showing the rear of the structure of Figure 1;

Figure 5 is a front elevation of the structure of Figure 1;

Figure 6 is a transverse section as seen at 6—6 of Figure 5;

Figure 7 is a front elevation similar to Figure 5, but showing the fastener in an unlocked position;

Figure 8 is a transverse section of Figure 7 as seen at 8—8 of Figure 7;

Figure 9 is a longitudinal section as seen at 9—9 of Figure 5;

Figure 10 is a perspective showing a modified form of fastener;

Figure 11 is a perspective showing the rear of Figure 10; and

Figure 12 is a section as seen at 12—12 of Figure 10.

The invention comprises essentially the provision of a hollow sleeve substantially rectangular in cross section and having an aperture extending across one face of the sleeve. A captive locking element having a wedge-shaped face is adapted to slide transversely of the sleeve so that in the unlocked position the wedge face of the locking element is removed from the bore of the sleeve in order to permit insertion of a strap or belt. When the strap is properly positioned in the hollow sleeve, the locking element may be forced into the sleeve so that the wedge face of the element jams the strap securely in the bore of

2

the sleeve and in effect crimps it over the edges of the aperture.

Referring now more particularly to the drawings, a hollow sleeve or buckle frame 15 is provided with an aperture 16 cut centrally in its front face 15a and in the preferred form extending partially over the top 15b of sleeve 15. The sides of aperture 16 are biased with respect to each other for a purpose to be described more fully hereinafter. The rear face 17 of the sleeve 15 is provided with a transverse slot 18 and also with an eye 19 to which one end of the belt 20 is attached.

The fastening or locking element 21 in the preferred form comprises a tapered wedge-shaped portion 21a to which is secured a button 22 which serves to retain the locking element 21 in the sleeve 15, said portion 21a having an outwardly extending projection 22a which serves to guide said locking element 21 in vertical sliding movement by means of slot 18. The locking element 21 extends horizontally as seen in Figures 1 and 2 to provide a top 23 which is substantially coextensive with the portion of aperture 16 in top 15b of the sleeve. The front or face of the locking device 21 extends downwardly in a flange 24 which likewise has biased edges corresponding generally with the edges of the aperture 16 in the front face 15a of the sleeve. Face 24 of the element is adapted to carry any suitable design such as an initial 25.

When the locking element 21 is raised in the sleeve so that button 22 is adjacent the top of slot 18, the belt or strap 20 may be readily inserted through the bore of sleeve 15 as shown in Figures 4 and 7. When belt 20 has been pulled through sleeve 15 to the desired position, downward pressure on the locking element 21 serves to securely crimp or wedge the strap 20 in the bore of sleeve 15. This crimping action is materially enhanced by the edges of aperture 16 as shown in Figure 9, so that the strap 20 is effectively clamped between the edges of wedge 21a and the edges of aperture 16. The biased position of these edges with respect to each other facilitates this crimping action and prevents the fastener 21 from becoming disengaged accidentally.

Referring now to Figures 10—12, sleeve 15' is provided with a biased aperture 40 in much the same manner as shown in conjunction with Figures 1—9. The sleeve 15' is extended to provide a suitable eye 41 to which the belt section 20 may be attached. The rear of sleeve 15' is, however, provided with two parallel slots 42 and 43 in which the ears 44 and 45 of locking element 46 may slide. The wedge-type locking action described previously with fastener 21 is substantially duplicated by means of the shape of element 46 which has an outwardly convex bulge 46a which faces the bore of sleeve 15' that serves to force the corresponding portion of belt 20 into

aperture 40 in the same manner as shown in conjunction with Figure 9. The form of Figures 10-12 is intended to be used primarily for straps or bands other than belt buckles in which there is no necessity for a decorative design or initial. Therefore, the front face 24 has been omitted and the top 47 of element 46 serves as a convenient means for manipulating said element 46 to lock and unlock the strap.

I have thus described an efficient, inexpensive strap fastener which is especially adapted for belt buckles that securely locks the strap or belt in place. The biased slant of the locking edges not only facilitates the actuation of the locking element, but assists in retaining a secure grip on the belt or strap.

Having thus described my invention, I claim:

1. A fastener for straps, belts and the like comprising a rigid tubular sleeve member having spaced parallel front and rear wall portions interconnected by side wall portions, said front wall having an opening therein extending transversely of said front wall continuously into one of said side wall portions, a locking element slideable transversely inwardly of said sleeve and including a wedge portion movable adjacent the sleeve rear wall in spaced confronting relation to the front wall opening, said member rear wall having a transverse opening therein, and rearwardly projecting means on said locking element slidably engaged in said rear wall opening to mount and guide said locking element with respect to said sleeve member.

2. A fastener for straps, belts and the like comprising a rigid tubular sleeve member having spaced parallel front and rear wall portions interconnected by side wall portions, said front wall having an opening therein extending transversely of said front wall continuously into one of said side wall portions, a locking element slideable transversely inwardly of said sleeve and including a wedge portion movable adjacent the sleeve rear wall in spaced confronting relation to the front wall opening, and a forwardly projecting head portion on the locking element arranged in the inner position thereof to reside in the portion of the opening in said one side wall of the sleeve flush with the surface thereof.

3. A fastener for straps, belts and the like comprising a rigid tubular sleeve member having spaced parallel front and rear wall portions interconnected by side wall portions, said front wall having an opening therein extending transversely of said front wall continuously into one of said side wall portions, a locking element slideable transversely inwardly of said sleeve and including a wedge portion movable adjacent the sleeve rear wall in spaced confronting relation to the front wall opening, a forwardly projecting head portion on the locking element arranged in the inner position thereof to reside in the portion of the opening in said one side wall of the sleeve flush with the surface thereof, said member rear wall having a transverse opening therein, and projecting means on said locking element slidably engaged in said rear wall opening to mount and guide said locking element with respect to said sleeve member.

4. A fastener for straps, belts and the like comprising a rigid tubular sleeve member having spaced parallel front and rear wall portions interconnected by side wall portions, said front wall having an opening therein extending transversely of said front wall continuously into one of said side wall portions, a locking element slideable

transversely inwardly of said sleeve and including a wedge portion movable adjacent the sleeve rear wall in confronting relation to the front wall opening, a head portion on the locking element arranged in the inner position thereof to reside in the portion of the opening in said one side wall of the sleeve, and a portion dependent from the said top portion of the locking element and spaced from said wedge portion arranged in the inner position of the element to reside in the front wall opening of the sleeve.

5. A fastener for straps, belts and the like comprising a rigid tubular sleeve member having spaced parallel front and rear wall portions interconnected by side wall portions, said front wall having an opening therein extending transversely of said front wall continuously into one of said side wall portions, a locking element slideable transversely inwardly of said sleeve and including a wedge portion movable adjacent the sleeve rear wall in confronting relation to the front wall opening, a head portion on the locking element arranged in the inner position thereof to reside in the portion of the opening in said one side wall of the sleeve, a portion dependent from the said top portion of the locking element and spaced from said wedge portion arranged in the inner position of the element to reside in the front wall opening of the sleeve, said member rear wall having a transverse opening therein, and means on said locking element slidably engaged in said rear wall opening to mount and guide said locking element with respect to said sleeve member.

6. A fastener for straps, belts and the like comprising a rigid relatively flat tubular sleeve member having spaced parallel front and rear wall portions of substantial transverse width interconnected by relatively narrow side wall portions, said front wall having a generally V-shaped opening therein extending transversely of said front wall and continuing into one of said side wall portions, a locking element slideable transversely inwardly of said sleeve and including a wedge portion movable adjacent the sleeve rear wall in confronting relation to the front wall opening, a head portion on the locking element arranged in the inner position thereof to reside in the portion of the opening in said one side wall of the sleeve, a portion dependent from the said top portion of the locking element and spaced from said wedge portion arranged in the inner position of the element to reside in the front wall opening of the sleeve, said member rear wall having at least one elongated transverse slot therein, and means on said locking element wedge portion engaged in said rear wall slot to slidably mount and guide said locking element with respect to said sleeve member.
